CHARLES S. BURTON, OF OAK PARK, ILLINOIS.

FUNCTION-MULTIPLYING DEVICE FOR AUTOMATIC MECHANISMS.

Application filed November 11, 1920. Serial No. 423,313.

To all whom it may concern:

Be it known that I, CHARLES S. BURTON, a citizen of the United States, and a resident of the village of Oak Park, in the county of Cook and State of Illinois, have invented 5 certain new and useful Improvements in Function-Multiplying Devices for Automatic Mechanisms, of which the following is a specification, reference being had to the accompanying drawings, forming a part 10 thereof.

The purpose of this invention is to provide in a pneumatically operated mechanism for selectively controlling the performance 15 of a plurality of functions, by providing means for the selective individual actuation of a major number of separate devices for different functions, by a minor number of actuators. It consists in the elements and 20 features of construction shown and described, as indicated in the claims.

In the drawings:

Figure 1 is a partially diagrammatic representation of a structure embodying this 25 invention, air duct connections being indicated by mere lines for showing their course, certain valve devices being shown as actual structures in sections.

Figure 2 is a section at the line, 2—2, on 30 Figure 3.

Figure 3 is a section at the line, 3—3, on Figure 2.

Figures 4, 5 and 6 are elevations of the second, third and fourth of the combining 35 plates or disks, the first plate being shown in Figure 2.

Figure 7 is a section similar to Figure 3, being a modification having a double series 40 of apertures for combinations, the section being made at such a plane as that indicated by the line, 7—7, on Figure 9.

Figure 8 is a diagrammatic view showing 45 certain pneumatics with their connections to the outlet from the fixed combining disk of the form shown in Figure 7.

Figure 9 is a diagrammatic view similarly indicating the air duct connections for certain functions.

Figure 10 is a face view of a disk employed in the modification shown in Figure 50 7.

Figure 11 is a side elevation of another species of the generic invention shown in the preceding figures.

Figure 12 is a section at the line, 12—12, 55 on Figure 11.

Figure 13 is a diagrammatic or quasi-tabular view for indicating a desirable and systematic distribution of the ports in the 60 several combining plates.

In the drawings there is shown an embodiment of this invention for the purpose of enabling a limited number of ducts of the tracker board co-operating with a like number of lines of perforation of a note 65 sheet of an automatic player for a keyed instrument, to selectively control the operation individually of a much larger number of devices functioning in their several ways for affecting the playing. But in the broad view of the invention it will be understood that it is not material whether the mechanism thus selectively operated relates to musical instruments' operation, or to some other mechanism having parts to be selectively operated or controlled. 70

In these drawings (see Fig. 1) there is shown a section of a tracker board, A, and of a note sheet, B, traveling across the tracker board for controlling the ducts of 80 the former by the perforations of the latter.

C^1 , C^2 , C^3 and C^4 are tubes leading from four ducts, c^1 , c^2 , c^3 and c^4 , of the tracker to primary pneumatics, d^1 , d^2 , d^3 and d^4 , in a partial vacuum chamber or primary pneumatic chamber, as it is commonly called, D, wherein these primary pneumatics operate the controlling valves, e^1 , e^2 , e^3 and e^4 , for controlling the motor pneumatics, E^1 , E^2 , E^3 and E^4 , which for such control are connected 85 by tubes, f^1 , f^2 , f^3 and f^4 , with the ports controlled by respective primary pneumatics contained in the chamber, D. This pneumatic action thus far described is of familiar character requiring no more particular 90 description, and of itself it does not consti- 95

tute the present invention, the purpose of which is to enable the four motor pneumatics which are selectively operated by the registration of apertures in the note sheets with the four ducts of the tracker respectively, to perform selectively a much larger number than four separate individual functions, and thereby to make the four tracker ducts accomplish what has heretofore required a much larger number of ducts, thereby reducing the requirement of tracker ducts for the auxiliary functions of a player mechanism, and making it possible, without lengthening the tracker and widening the note sheet, to have enough ducts and lines of perforations to play the entire 88 notes of a piano, and in addition to control automatically the large number of auxiliary functions desirable for complete and accurate characterization of the music produced.

Each of the motor pneumatics, E^1 , E^2 , E^3 and E^4 , (see Figs. 2 and 3) is connected by a link, G , attached to its moving leaf with one of the four disk members, H^1 , H^2 , H^3 and H^4 , constituting a group of combining plates which are mounted side by side for parallel movement between opposite side walls, K , K^1 , of a casing which may completely enclose them and the operating pneumatics. In the form shown in the principal figures these combining plates are mounted for rotation on a fixed stud axle, H^x , secured to one of the side walls, K , and extending through the opposite wall, K^1 , and said combining plates are assembled on said axle between a member, H^y , which is yieldingly pressed toward the member, H , by a spring, H^z , retained on the stud axle by a tensioning nut and washer h^x and h^y ; whereby the four disk members, H^1 , H^2 , H^3 , and H^4 , are held in compact relation, spaced apart by rubber bushings, S , hereinafter more particularly described. These combining plates are actuated back and forth by the back-and-forth movement of the moving members of the respective motor pneumatics with which they are connected, the length of the step action being limited by a stop bar, 1, carried on the fixed member, H , on which all the combining plates, H^1 , H^2 , H^3 and H^4 , are mounted for their said parallel movements, said plates having each two stop lugs, h , for stopping against said bar in the right hand and left hand movements respectively. Each of said movable members has a plurality of ports arranged in succession along the path of its step movement, the extent of each member in the path of the step movement being sufficient to contain a relatively large number of ports, that is to say, being a relatively large multiple of the length of the step movement. In the embodiment of the invention which is shown in Figures 2 to 10, inclusive, these parallel moving members are disks mounted for rotation about a

common axis, the path of movement, therefore, being circular about that axis, and the length of step movement being one-thirty-second of a full revolution thus creating a possibility of thirty-two different ports in the length of the path of movement. The ports are each designated by a letter, h , with an exponent which is the number of the port in right-hand order from any selected starting point;—that is to say, the port at the selected starting point being indicated by h^1 , the succeeding ports in right-hand order have their exponents increasing up to 32, so that the last port to the right,—the one next to the left of the starting point,—is designated at h^{32} . Ports are not provided in all the members, H^1 , H^2 , H^3 and H^4 , at all the step limits throughout the circuit or path of movement, but on the contrary, each member has certain blank or portless areas, i. e., certain step limits are without ports, and these portless steps are distributed differently on the several movable members, H^1 , H^2 , H^3 and H^4 . The fixed members, H , and H^x between which all the movable members, H^1 , H^2 , H^3 and H^4 , are rotatably mounted have ports at all (except as hereinafter stated) of the thirty-two steps in the circle in which ports of the movable members are located. (See Figs. 9 and 10.) At only two points,—that is, at two of the step limits out of the entire thirty-two (see points 29 and 30 on Fig. 13),—all four of the members, H^1 , H^2 , H^3 and H^4 , have a port, so that there is registration of these ports through-and-through all four members at the normal position of rest of said members, only at two points in the entire circumference; and at these points the fixed member, H , may have the ports omitted, or if present, (as shown,—see Fig. 8, showing all 32 ports) they are not connected with any device to be operated, and are therefore functionless. The distribution of the portless areas or points on the several members, H^1 , H^2 , H^3 and H^4 , is such that at the normal position of rest, there is no through-and-through registration of operative ports, and so that a one-step movement,—which is all that is possible,—of one of the members away from that position of rest, will complete the through-and-through registration of the ports at one point, and movement of another of the members one step will complete the registration at another point, the movement of a third member one step will complete registration at a third point, and the movement of a fourth member one step will complete the registration at a fourth point, and so that the movement of the members by twos will complete registration at as many different points as the number of combinations of two-and-two which are possible of four members, (being six), and that the movement of the members by threes at

one step will complete the registration of all four at as many other different points as the number of possible combinations by threes (which would be four); and, as above noted, all four members having registered ports at one point in the rest position, the movement of all four members one step will bring these four registered ports into registration with a port of the fixed member, H, thus completing registration through-and-through of all four members and the fixed member. Fifteen combinations or groups being possible of any four registration numbers (counting each single one as a group), it will be seen that it will be possible, by simultaneously actuating either, any one of the four members, H^1 , H^2 , H^3 and H^4 , or any two of them or any three of them, or all four of them, to thereby produce registration through-and-through for connection with any one of the fifteen tubes, J, with an exponent, which are connected with certain fifteen ports of the fixed member, H, whose ordinal is the exponent of J. It will also be noticed that the fifteen registrations indicated are all effected by movement of the disk in one direction, say to the right. Another fifteen registrations may be effected similarly by moving the members, H^1 , H^2 , H^3 and H^4 , to the left, thereby effecting registration through-and-through with any one of fifteen additional ports of the fixed members and with any one of the tubes, j, with an exponent which is the ordinal of the port, connected with them respectively. Each of the tubes, J and j, (except one hereafter mentioned as leading to a duplex pneumatic for a particular purpose) may be understood as leading to a pneumatic unit indicated conventionally at L (Figure 1), comprising a motor pneumatic, L', for performing any specific function required in the operation of the mechanism for which the device is designed, and in the present instance for performing any one of the various auxiliary functions in an automatic playing mechanism.

By reference to Figure 13 in which the circles numbered I, II, III and IV, show the distribution of the ports and portless areas of disks, H^1 , H^2 , H^3 and H^4 , respectively, and the thirty-two numbered radial lines indicate the position of the thirty-two possible outlet ducts of the J and j series, (fifteen), plus two ductless or blind ports, it may be understood what disks being simultaneously given a single step movement to the right or to the left, will thereby effect through-and-through registration of the ports of the several disks, and so open air communications with tubes of the two series, j and J, for operating function-performing devices, as motor pneumatics for striking notes, or other parts requiring movement for auxiliary functions, in an automatic player,

or whatever mechanism is served by the device.

The following table shows the through-and-through registrations which are obtained by the different combinations which are possible to the left and to the right.

For actuating the members H^1 , H^2 , H^3 and H^4 , selectively either to the right or to the left, according to the particular functions to be immediately performed by the group of pneumatics next to be brought into action, each of the pneumatics, E^1 , E^2 , E^3 and E^4 , is made double,— that is to say, its moving member is interposed between two fixed members connected to each of them by a separate bellows, said bellows chambers having separate connections with the exhaust devices for collapsing them to give the actuating stroke, which will be in one direction or the other according to which of the bellows is thus operated. For controlling these double bellows, tubes, m^1 , m^2 , m^3 and m^4 , lead from the inner side bellows members of said pneumatics, E^1 , E^2 , E^3 and E^4 , respectively, to ports, x^1 , x^2 , x^3 and x^4 , in a port board, EE, and from the outer side bellows members, tubes n^1 , n^2 , n^3 and n^4 , lead to ports, y^1 , y^2 , y^3 and y^4 , in the same port board, the ports of the first set alternating with the ports of the second set in said board; and a valve board, ee, is mounted upon said port board, EE, with range of movement under the action of the bellows L^x and L^{x^1} to register its ports, e^{x^1} , e^{x^2} , e^{x^3} and e^{x^4} respectively, either with the ports, x^1 , x^2 , x^3 and x^4 , or with the ports, y^1 , y^2 , y^3 and y^4 . The tubes, f^1 , f^2 , f^3 and f^4 , are connected respectively with the ports, e^{x^1} , e^{x^2} , e^{x^3} , e^{x^4} , of the valve board, ee.

A duplex pneumatic unit, L^x, controlled as to one of its bellows by any selected tube of the fifteen tubes, J, with numeral exponents, and as to the other bellows by the corresponding tube, j, with numeral expo-

nents, has the moving board, L^{x1} , connected with the valve board, ee , for actuating the valve board in one direction for registering one set of ports, and for actuating said board in the other direction for registering the other set of ports. The two tubes, shown as selected being J^6 and j^{21} , are respectively rendered operative for bringing into service the pneumatics which they respectively control by the same disk movements, which according to the foregoing table are of disks II, III and IV (see Fig. 13), only in the case of the duct, j^6 , the movement is to the left, and in the case of the duct, J^{21} , the movement is to the right; but the same apertures or group of apertures in the note sheets for moving the three disks mentioned will always mean and will always produce a reversal of the direction of the step movement of the members, H^1 , H^2 , H^3 and H^4 . If the last preceding movement was to the right, the tube, J^6 , will be brought into operation and the valve board, ee , will be shifted so that the step action will be to the left; and if the last step action was to the left, the tube, j^{21} , will be brought into action and will shift the valve board in the opposite direction, causing the next step action to be to the right.

In auto-pneumatic playing devices in connection with which this invention may be applied, certain of the auxiliary functions to be performed are sometimes required to be performed simultaneously with one, two or even with three other auxiliary functions; and the present invention may be adapted to such simultaneous performance of several functions by the following means which will now be described.

At the side of the group of members, H^1 , H^2 , H^3 and H^4 , opposite that at which the fixed member, H , is situated, there is mounted upon the common axis of said members, H^1 , H^2 , H^3 and H^4 , a valve member, H^5 ; and the several members, H^1 , H^2 , H^3 and H^4 , which have ports h^1 to h^{32} , to be registered through-and-through for any of the functions with which other functions are to be performed simultaneously, are provided with ports denoted by h^x with a numeral exponent, said ports being radially aligned respectively with the ports, h , having the same numerical exponent of the outer circle already described, said ports, h^x with an exponent, being arranged in a circle concentric with said principal or outer circle of ports, h , with exponent. The valve member, H^5 , has a normal position at which it closes all of the ports of the inner circle of ports, h^x , and uncovers them all upon movement of said valve member a certain step from its said normal position of closure. An additional tracker duct and line of controller sheet perforations may be used for actuating the valve member, H^5 ,

by means of a pneumatic unit, M , the perforations in the line for controlling it being made to hold the valve at open position throughout any period of travel of the note sheet through which simultaneous performance of two functions is desired, the valve member, H^5 , being preferably returned to closing position by a spring, M^1 , when the action of the pneumatic unit, M , ceases at the termination of the aperture (or group of closely successive apertures having the effect of a continuous aperture) in the control sheet which covers it.

When the total number of auxiliary functions desired is less than the number of combinations available, (which is 28 when only four original tracker ducts are utilized, one combination of each total of 15 being used for changing the direction of step movement) the excess may be taken advantage of for two or more simultaneous functions, dispensing with the valve member, H^5 , and with the use of the additional tracker ducts for controlling it. This is done in the following manner: Any particular function which is sometimes to be performed alone, and sometimes to be performed simultaneously with another function, has appropriated to it two combinations out of a total possible fifteen. For one of them, the members, H^1 , H^2 , H^3 and H^4 , and the fixed member, H , have ports only in the outer or principal circle, and for the other function, said members have additional ports in the inner or secondary circle; and tubes for controlling the second function lead from the ports of the fixed member, H , in the second circle into communication with tubes from the ports of the first circle which pertain to said second function. Four illustrations of this expedient are shown in the drawings. Radially aligned with the ports, h^6 , h^{12} , h^{18} and h^{24} , of the principal circle, the second circle (see Fig. 9) in all the members, H^1 , H^2 , H^3 and H^4 and H , has ports, h_{x^6} , $h_{x^{12}}$, $h_{x^{18}}$ and $h_{x^{24}}$, and the tubes, j^6 , j^{12} , j^{18} and j^{24} , leading from these ports in the fixed member, H , are all connected into the tube, J^9 , leading from the port, h^9 . The ports, h^6 , h^{12} , h^{18} , and h^{24} , may be understood as constituting one set of ports controlling the section of solo groups (for accentuating the solo in playing). Four other ports, as for example, h^2 , h^8 , h^{14} , and h^{20} , are also connected for controlling the same functions respectively; and the tubes, j^2 , j^8 , j^{14} and j^{20} , leading from the ports, h^2 , h^8 , h^{14} and h^{20} , are connected respectively with the tubes, j^6 , j^{12} , j^{18} and j^{24} , leading from the ports, h^6 , h^{12} , h^{18} and h^{24} , as seen at 40, so that either of the two combinations will perform the respective solo functions. The port, h^9 , may be assumed to be the control port for any function which is to be performed simultaneously with the solo functions, as for ex-

ample, for controlling the soft pedal for softening the accompaniment. When the solo functions are to be performed alone, the combination for ports, h^2 , h^8 , h^{14} and h^{20} , will be used, and when the solo functions are to be performed simultaneously with the soft pedal functions, the combination for ports, h^6 , h^{12} , h^{18} and h^{24} , will be used. It will be evident that a similar expedient may be employed for performing simultaneously more than two functions,—that is, a third circle of ports may be used having ports at certain radial lines where three through-and-through registrations will be obtained from the same combination. This is indicated by ports marked h^{y6} , h^{y12} , h^{y18} and h^{y24} , in Figure 10. The method of carrying out the connections from these ports of the third series may be understood from the foregoing description as to the connections from the ports of the second series without further illustration.

It will be obvious that instead of members mounted for step movement about a pivot so that the path of the step movement and of the distribution of the several steps or stations is circular, the members having the ports to be registered may be mounted for sliding in a straight-line path from that of a similarly constructed fixed member. This modification is shown in Figures 11 and 12, and requires no particular description beyond noting that the members and their several features are designated in the same manner as those of the pivoted construction of the earlier figures, with the substitution of the letter p for the letter h , the tubes running from the board arranged in a straight line in this form bearing the same designation as the tubes running from the ports arranged in circles in the other form.

For safety against air leakage between the consecutive movable ported members or combining plates which if it should occur would tend to cause action to take place through some of the tubes beside those which were in through-and-through registration, it is preferable to interpose between the consecutive combining plates stationary plates, R , each of them having ports at all the points at which through-and-through registration of the movable plates is at any time to occur. As a further insurance against air leakage, it is preferable to provide each of the ports of the stationary plates, R , with slightly protruding marginal lips of relatively soft material for seating upon the faces of the adjacent movable members or combining plates. Such marginal lips are most effectively and conveniently provided by making bushings of suitable soft material, such as rubber, each containing the ports, such bushings, S , being set through the plates, R , and protruding very slightly at each end,—that is, at each side of said

plates. The plates, R , are held in fixed position by having radially projecting lugs, R^1 , extended out at ninety-degree intervals, and engage posts, P , which bind the opposite case walls, K^1 and K^2 , together.

In the motor pneumatics, E^1 , E^2 , E^3 and E^4 , the expanding springs, E^{40} , tend to return the oscillating board of the pneumatic to middle position and thereby to return the combining plate with which the pneumatic is connected to its normal rest position. Such return may be assisted and insured by providing a stretched spring, E^* , connected at any convenient point in the circumference of the combining plate and stretched radially of the plate at the rest position of the latter to a point of attachment at w , on the frame or casing, and providing also a detent, W , having a V -shaped nose for engaging a slight V -shaped notch, W^1 , positioned on the periphery of the plate at proper points for such engagement at rest position of the plate.

I claim:—

1. A device for the purpose indicated comprising a plurality of combining members mounted for movement in parallelism with each other through a definite step distance; means for positioning them all normally at a selected starting or rest position, and means for giving them individually in selected groups a definite step movement from said normal rest position; each member having a series of ports arranged in succession along the path of the step movement; each member having a blank or portless area at a point along said path at which other members have ports positioned for registration, and having a port in said path at step distance from said portless area; the several members differing as to the points in the path at which said portless areas occur; whereby a movement of different combining members a step distance from the normal rest position produces through-and-through registration of ports in all the members at different points in the path of movement.

2. In a construction defined in claim 1, a fixed member adjacent one side of the group of members having the step movement, said fixed member having ports and ducts leading therefrom at step intervals along a path parallel to the path of movement of the movable members at points for registering with the through-and-through registered ports of the movable members.

3. In a construction defined in claim 1, each member having two or more parallel series of ports, the ports of each series being arranged as called for by said claim 1; whereby the same step movement of the same member or combination of members will effect registration through-and-through them at certain points simultaneously in several series.

4. In the construction defined in claim 1, the means for step actuation of the ported members, being adapted for moving them in either direction from normal position, and means for shifting the connection of said operating means to change the direction of the step movement.

5. In the construction defined in claim 1, the means for step actuation of the ported members, being adapted for moving them in either direction from normal position, and having alternative connections with a source of energy causing it to operate alternatively for movement in one direction or the other and means for shifting the connection of said actuating means to change the direction of the step movement, said last mentioned means comprising pneumatic connections from one line of through-and-through registered ports whose registration is produced by movement of a selected combination of the movable members.

6. In the construction defined in claim 1, fixed plates interposed between the movable ported members, said plates having ports registering with the through-and-through registered ports of said movable members.

7. In the construction defined in claim 1, fixed plates interposed between the movable

ported members, said plates having ports 30 registering with the through-and-through registered ports of said movable members, the ports of the fixed members being provided with marginally protruding lips of relatively soft material for air tight seat- 35 ing on the adjacent movable members.

8. A device for the purpose indicated comprising a plurality of disks mounted for turning individually about a common axis; means for positioning the several disks in a predetermined normal relation to each other about said axis; means for giving them individually a definite angular step movement about the axis away from their respective normal positions; each disk having 45 a plurality of ports arranged in a circle about the axis at distances of which the step movement is a common divisor; each disk having ports omitted at certain points in the circle at which other disks are provided with 50 ports, and the several disks differing as to the points in the circle at which the ports are omitted.

In testimony whereof, I have hereunto set my hand at Chicago, Illinois, this 10th day 55 of November, 1920.

CHARLES S. BURTON
